United States Patent Office.

JOHN MAGEE, OF NEW YORK, N. Y., ASSIGNOR TO BIGELOW CARPET COMPANY, OF CLINTON, MASSACHUSETTS.

Design No. 5,032, dated June 20, 1871.

DESIGN FOR CARPET.

The Schedule referred to in these Letters Patent and making part of the same.

all whom it may concern:

Be it known that I, JOHN MAGEE, of New York, in the county and State of New York, have invented a new and original Design for a Carpet; and to hereby declare that the following is a full, clear, and exact description thereof, which will enable others skilled in the art to make and use the same, reference being had to the accompanying drawing forming part of this specification.

The photograph represents a quarter-section of my design.

This design relates to a new foliaged border portion of a central figure, and to a new general design for a carpet or other fabric.

The central figure A, of which one-fourth part is shown, and which, if complete, forms a four-armed rosette, has a foliaged border, B, of new design, which could also be advantageously applied to figures of other form.

The general design of the fabric is fully shown.

I claim as my invention—

1. The design of the foliage border B, as shown.
2. The design for a carpet, as shown.

JOHN MAGEE.
